POP-UP TARGET

Clair Omar Musser, Studio City, Calif., assignor to Knickerbocker Plastic Co. Inc., North Hollywood, Calif., a corporation of California

Application June 29, 1956, Serial No. 594,855

5 Claims. (Cl. 273—102.1)

This invention relates to new and improved toy targets, and more specifically to toy targets of the so-called "pop-up" variety.

The toy field is at this time an extremely competitive industry where minor advances or improvements frequently make the difference between commercial success and failure. Currently there is a demand for toy targets capable of being used with projectiles fired from spring loaded toy pistols and the like. Obviously toy targets as a class have long been known. In order to make such targets attractive for commercial purposes it is necessary to incorporate within them some sort of an operative mechanism providing other results than are conventionally achieved with targets.

A basic object of this invention is to provide in toy targets an operative mechanism which serves to release part of the target itself when the target is correctly engaged by a projectile so that the released part "pops up" or is otherwise propelled away from the basic part of the target itself. For convenience of explanation the basic part of such a target is termed herein a "target surface," although this part may include other than mere means defining a surface. The term "target member" is employed in this specification to designate the part of a toy target which is adapted to be ejected from the target surface when the target is correctly engaged; and the term "target actuator" is used to describe the part of the target which is adapted to be engaged by a projectile so as to cause ejection of the target member. These terms are not to be taken as limiting the invention since they are only employed for descriptive purposes.

Another basic object of the invention is to provide toy targets of the "pop-up" variety which can be assembled for shipment or display in approximately the final operative configuration, and which are incapable of being operated so as to eject a target member when so assembled. This is considered to be important for commercial reasons since toy targets of this invention cannot be satisfactorily shipped when assembled in an operative manner without special shipping precautions because of the danger of the target actuators employed with them being engaged so as to operate the targets themselves. It is also considered important since the purchasing public likes to play with toys on display. If the pop-up targets of the invention were displayed after being assembled in an operative manner difficulties would arise from actuation of these targets by prospective purchasers. The essential nature of the toy targets herein described can be visualized by assembling these devices as indicated in this paragraph, and yet when so assembled these toy targets can not be actuated.

Further objects of the present invention are to provide toy targets which are simple and inexpensive to construct and which are very reliable in operation. Another object of the invention is to provide toy targets which may be considered "child-proof" in that they are very difficult to damage. Still further objects of the invention as well

2

as many specific advantages of it will be more fully apparent from the remainder of this description, the appended claims, and the accompanying drawings in which:

Fig. 1 is a prospective view of the toy target of this invention;

Fig. 2 is a side cross sectional view taken at line 2—2 of Fig. 1;

Fig. 3 is a cross sectional view taken at line 3—3 of Fig. 2;

Fig. 4 is a cross sectional view taken at line 4—4 of Fig. 2;

Fig. 5 is a side elevational view of toy target shown in Fig. 1 showing this toy target assembled in an inoperative manner for display, shipment or the like;

Fig. 6 is a cross sectional view taken at line 6—6 of Fig. 5; and

Fig. 7 is an expanded view showing the construction of various parts employed in the toy target illustrated.

In all figures of the drawing like numerals designate the same parts. It is to be understood that this invention is not to be considered as being limited in any respect by the accompanying drawing inasmuch as the relative sizes and shapes of the various parts employed can be changed through the mere exercise of routine engineering skill.

Further, the essential appearance of the toy target illustrated can be altered in any desired manner so as to achieve various commercial sales potentials. As an example of this, one embodiment of the target of this invention is formed so as to illustrate a common nursery rhyme with a figure sitting upon a wall. When the target is actuated this figure literally pops off the wall.

In order to understand this invention it may be stated in essentially summary form that it involves targets of the class indicated, each of which includes: a target surface;

a target member removably mounted adjacent to this target surface; a target actuator positioned adjacent to the target surface; and means mounted on the target surface connecting the target actuator and the target member so that when said target actuator is engaged by

a projectile under force the target member is caused to be ejected away from the target surface. The invention is more precisely summarized and/or defined in detail by the appended claims.

In order to understand the actual nature of the invention it is necessary to refer to the various figures of the drawing showing what may be considered a preferred embodiment of it. Here there is shown a toy target 10 having a target surface 12 formed of a sheet of pressed board or the like.

This surface is adapted to be held in a vertical position by means of bases 14 engaging it in a conventional manner; it can obviously be mounted or supported by other equivalent means. Upon the rear of the surface 12 there is located a generally U-shaped spring retainer 16 having an open top 18, a bottom slot 20, and a side opening 22.

This spring retainer 16 is formed so that a generally U-shaped lever arm 24 may be positioned over it with a small extension 26 on the bottom of the lever arm 24 extending through the slot 20 into the spring retainer 16.

This extension is adapted to carry one end of a coil spring 28 positioned within the spring retainer 16. Preferably it is provided with a small bent over end 30 engaging the bottom of the spring 28 so as to prevent the extension 26 from sliding out of the slot 20.

At the top of the lever arm 24 there is provided a small projection 32 which is adapted to fit within the side opening 22 in order to engage the wall of a notch 34 formed in an arm 36 extending from the back of a target member 38 when this arm 36 is positioned within the

spring retainer 16 so as to compress the spring 28. In effect the projection 32 serves as a latch member, and the projection 32 and the notch 34 together serve essen-

tially as "latch means" holding the target member 38 in an operative position.

An important feature of the present invention lies in the fact that when the target member 38 is moved so as to insert the arm 36 through the open top 18 a curved bottom 40 of the arm 36 engages the spring 28. As pressure is applied to the target member 38 this coil spring 28 is compressed, and force is transmitted to the extension 26 causing the lever arm 24 to rotate from the position shown in phantom in Fig. 2 until the projection 32 is locked within the notch 34. The target 10 is then in a "loaded" configuration, and is assembled for use. It will be realized that in this assembled configuration that the spring 28 and that the "latch means" indicated above are mounted on the rear of the target surface 12.

When so assembled and used, a target actuator 42 on the front of the surface 12 is engaged by a projectile or the like, and the force applied to this particular part is transmitted through arms 44 attached to the sides of the lever arm 24 so as to cause the lever arm 24 to rotate back to the phantom position shown in Fig. 2. When the lever arm 24 is so moved it is in a "released" position, and the spring 28 automatically propels the target member 38 away from the surface 12. The arms 44 in the embodiment of the invention shown pass through an opening 46 in the surface 12 so as to ride along both sides of the spring retainer 16.

With the preferred construction of the invention the actuator 42 and the member 38 are both formed of the same material as the surface 12, and the exposed portions of all three of these members are preferably printed or otherwise manufactured so as to present, in effect, an interrelated picture. All of the other parts of the target 10 are conveniently formed out of metal by established techniques, and may be assembled by various conventional procedures.

It is specifically noted that, if desired, the target member 38 may be positioned with the arm 36 between the lever arm 24 and the spring retainer 16 as indicated in Fig. 5 for shipping or displaying this target. When so assembled the arm 36 is merely located and, if desired, wedged to a slight extent between these two parts. The U-shape of the lever arm 24 prevents the target member 38 from moving from side to side when so assembled. Thus, the lever arm 24 provides an effective holding means for positioning the target member in approximately the final operative position. When so assembled the target 10 is incapable of being actuated, and may be conveniently shipped or displayed without danger of target actuation.

Those skilled in the art to which this invention pertains will realize that a number of modifications may be made in the structure shown without departing from the basic nature of this invention. For this reason the invention itself is to be considered as being limited only by the appended claims.

I claim:

1. A pop-up target of the class described which comprises: a target surface; means for supporting said target surface in a vertical plane; a U-shaped spring retainer attached to the rear side of said target surface, said spring retainer having an open top, a bottom slot, and a side opening; a generally U-shaped lever arm having an extension located on the bottom thereof and a projection located at the top thereof positioned over said spring retainer with said extension projecting into said bottom slot, said projection being adapted to fit within said side opening; a coil spring positioned within said spring retainer so as to rest against said extension on said lever arm; a target member having a dependent arm extending therefrom, said arm having a notch formed therein, said target member being adapted to be located on said target surface through the insertion of said dependent arm through said open top within said spring retainer, said dependent arm engaging said coil spring and compressing said coil spring, and through force transmitted to said extension by said coil spring causing said lever arm to rotate so that said projection extends through said side opening and engages said notch in said arm; means defining an opening in said target surface adjacent to said spring retainer; arm means attached to said lever arm and extending through said opening on said target surface; and a target actuator attached to said arm means whereby when said target actuator is engaged by a projectile force is transmitted to said lever arm.

2. A pop-up target which includes: a target surface having front and rear sides; a spring retainer secured to the rear side of said target surface, said spring retainer having an open top and a passage leading from said open top along the rear side of said target surface; a coil spring positioned within said passage in said spring retainer; a target actuator mounted on the front side of said target surface so as to be movable with respect to said target surface; a lever arm rotatably mounted on said spring retainer, said lever arm having a projection formed thereon and being attached to said target actuator so as to be capable of movement when said target actuator is engaged by a projectile; a target member having an arm extending therefrom, said arm having a notch formed therein, said arm extending into said spring retainer and engaging said spring so as to distort said spring, said notch in said arm being engaged by said projection whereby when said target actuator is engaged by a projectile, said lever arm is disengaged from said notch, and said spring is released so as to move said target member away from said target surface.

3. A pop-up target of the class described which comprises: a target surface; means for supporting said target surface in a vertical plane; a U-shaped spring retainer attached to the rear side of said target surface, said spring retainer having an open top, a bottom slot, and a side opening; a lever arm having an extension located on the bottom thereof and a projection located at the top thereof positioned on said spring retainer with said extension projecting into said bottom slot, said projection being adapted to fit within said side opening; a coil spring positioned within said spring retainer so as to rest against said extension on said lever arm; a target member having a dependent arm extending therefrom, said arm having a notch formed therein, said target member being adapted to be located on said target surface through the insertion of said dependent arm through said open top within said spring retainer, said dependent arm engaging said coil spring and compressing said coil spring, and through force transmitted to said extension by said coil spring causing said lever arm to rotate so that said projection extends through said side opening and engages said notch in said arm; means defining an opening in said target surface adjacent to said spring retainer; means attached to said lever arm extending through said opening on said target surface; and a target actuator attached to said arm means whereby when said target actuator is engaged by a projectile force is transmitted to said lever arm.

4. A pop-up target comprising a target surface having front and rear sides; a spring retainer secured to the rear side of said target surface, said spring retainer having an open end and a passage leading from said open end; a target member separate from said target surface and having front and rear faces and being disposed adjacent to an edge of said target surface so that its front face is visible from the front of the target; an arm attached to the rear face of said target member and removably projecting into said passage in said spring retainer through the open end thereof; a spring in said retainer bearing against the end of said arm to apply a force thereto tending to eject said arm from said retainer; a target actuator mounted adjacent the front side of said target surface for movement in a rearward direction when struck by a projectile; and latch means connected to said actuator for movement therewith and including a portion disposed in locking engagement with said arm when said actuator is

5. A pop-up target which includes: a target surface having front and rear sides; a spring retainer secured to the rear side of said target surface, said spring retainer having an open end and a passage leading from said open end; a target member separate from said target surface and having front and rear faces and being disposed adjacent to an edge of said target surface so that its front face is visible from the front of the target; an arm attached to the rear face of said target member and removably projecting into said passage in said spring retainer through the open end thereof; a spring in said retainer bearing against the end of said arm to apply a force thereto tending to eject said arm from said retainer; a target actuator mounted adjacent the front side of said target surface for movement in a rearward direction when struck by a projectile; and latch means connected to said actuator for movement therewith and including a portion disposed in locking engagement with said arm when said actuator is

in its forwardmost position and disposed out of contact with said arm when said actuator is in its rearwardmost position, so that rearward movement of said actuator in response to the impact of a projectile frees said arm from the restraint of said latch means and permits said arm and the attached target member to move under the influence of said spring.

5. A pop-up target comprising a target surface having front and rear sides, a member positioned on the rear side of said target surface and having an open passage extending from one of its ends, a target member separate from said target surface and having front and rear faces and being disposed adjacent to an edge of said target surface so that its front face is visible from the front of the target, an arm attached to the rear face of said target member and removably projecting into the open end of said passage, a target actuator mounted adjacent the front side of said target surface for movement in a rearward direction when struck by a projectile, latch means connected to said actuator for movement therewith and including a portion disposed in locking engagement with said arm when said actuator is in its forwardmost position and disposed out of contact with said arm when said actuator is in its rear-

wardmost position, and spring means applying a force tending to move said actuator to its forwardmost position and applying a force to said arm tending to eject said arm from said passage, whereby rearward movement of said actuator in response to the impact of a projectile frees said arm from the restraint of said latch means and permits said arm and the attached target member to fly away from said target surface under the influence of said spring means.
